CLAIM

The ornamental design for a capsule for use in a personal vaporizer, as shown and described.

DESCRIPTION

FIG. 1 is an upper perspective view of a capsule for use in a personal vaporizer, showing our new design; FIG. 2 is an exploded upper perspective view of the capsule, showing the body of the capsule and the cap thereof disassembled; the broken lines appearing on FIG. 2 are a drawing convention showing the relationship between parts and form no part of the claimed design.

FIG. 3 is a cross-sectional view of the capsule taken at line 3-3 in FIG. 5;

FIG. 4 is an end view of the capsule, the opposite end having the same appearance;

FIG. 5 is a side view of the capsule, the opposite side having the same appearance;

FIG. 6 is a top view of the capsule;

FIG. 7 is a bottom view of the capsule; and,

FIG. 8 is a lower perspective view of the capsule.
